ELECTRICAL APPARATUS

Application filed April 23, 1931. Serial No. 532,321.

The present invention relates to electrical apparatus and more particularly to means for preventing sparking across the contacts of a control device of the contact type, as 5 for example, a voltage regulator.

In the operation of electrical contacting devices, as for example contact voltage regulators, as in the operation of any electrical circuit wherein current is interrupted by the 10 making and breaking of electrical contacts, considerable sparking takes place across said contacts, which in many instances is so great as to cause the fusing together of the contacts, thereby destroying the control device and 15 causing other hazardous failures of systems in which such control devices are employed. This is particularly true in installations where a contact voltage regulator is employed with a direct current generator, the shunt 20 field of which has a relatively high inductance and upon the making and breaking of the regulator contacts this relatively high inductance causes a sudden voltage surge to be induced in the generator field winding. The 25 electromotive-force thus produced by self-induction causes the excessive sparking across the contacts. Accordingly, one of the objects of the present invention is to provide novel means whereby excessive sparking, due to 30 the self-induced electromotive-force, is substantially eliminated and prevented.

Another object is to provide in combination with an electric current generator having a voltage regulator of the contact type for controlling the output thereof, novel means associated with the regulator contacts whereby 35 sparking across said contacts is eliminated and the fusing of the latter prevented.

Another object is to provide in combination 40 with an electric current generator having a voltage regulator in which the contacts are adapted to operate at relatively high speeds for controlling the voltage output of said generator, novel means associated with the 45 voltage regulator and the field of the generator, whereby sparking across said contacts is substantially eliminated and fusing thereof prevented.

A further object is to provide in combination 50 with an electrical contacting device, novel

means whereby electrical disturbances in circuits associated with or operating in the vicinity of said contacting device, due to the sparking produced by the operation of the latter, are substantially eliminated or prevented. 55

Still another object of the invention is to provide in combination with an electric current generator having a field winding of relatively high inductance and a voltage regulator of the contact type wherein the contacts are adapted to operate at relatively high speeds for controlling the voltage output of said generator, novel means embodying impedance elements associated with the voltage 60 regulator contacts and the generator field, whereby sparking across said contacts due to the self-induced electromotive-force produced in the generator field by the operation of the contacts, is substantially eliminated 65 and whereby disturbing oscillations which would otherwise be produced by the sparking action, are suppressed at their source. 70

The above and other objects and advantages of the invention will be more fully apparent from a consideration of the detailed description which follows, taken together with the accompanying drawing wherein is illustrated one embodiment of the invention. It is to be expressly understood, however, 75 that the drawing is for the purpose of illustration and description only and is not designed as a definition of the limits of the invention, reference being had for this purpose to the appended claims. 80

The single figure of the drawing is a wiring diagram of one form of electrical circuit arrangement embodying the present invention. 85

The novel means embodying the invention 90 are particularly adapted to be employed in combination with a direct current generator which is arranged to supply electrical energy to various types of auxiliary electrical apparatus, as for example storage batteries, 95 lighting equipment and radio receiving and transmitting systems (not shown) and having a voltage regulator of the contact type in which the contacts are arranged to operate at relatively high speeds for maintaining the 100

generator output voltage substantially constant. The voltage regulator is of the type which is illustrated, described, and claimed in a co-pending application of Charles I. 5 McNeil, Serial No. 332,998, filed January 16, 1929 and assigned to the same assignee as the present application.

Referring to the drawing, the armature of the generator to be regulated is indicated at 10 1, the field winding which in the present instance is of a relatively high inductance is indicated at 2, and the field resistance at 3, said winding and resistance being connected in series across positive and negative output 15 leads 4 and 5 respectively.

The voltage regulator comprises a pair of relatively movable contacts 6 and 7 which are normally closed, thereby shunting the resistance 3. Contact 7 is mounted on a vibrating armature 8 which is pivotally mounted in any suitable manner, and adjustable resilient means are provided, such as a coil spring 9 which is operatively connected to said armature, to normally maintain contact 7 in engagement with contact 6.

An electro-magnet having a core 10 which is preferably laminated and made of suitable magnetic material, such as soft iron, is associated with armature 8, and spring 9 is 20 so adjusted that when the voltage of the generator rises above a predetermined value, the electro-magnet is effective to overcome the tension of said spring and move contact 7 out of engagement with contact 6, whereupon 25 the field resistance 3 is placed in circuit with the field 2. The resistance of the field circuit is now of such value as to prevent the desired amount of field current from flowing, thereby producing a reduction in the generator 30 voltage. This dropping of the voltage weakens the magnetic field of the electro-magnet to such an extent that the contacts 6 and 7 are closed by the spring 9 to short-circuit the resistance 3, whereupon the field flux and 35 armature voltage will again build up.

The core 10 of the electro-magnet carries a winding 11 which is in series with a suitable resistance 12, the winding and resistance being connected across the output leads 4 and 5. 40 The magnetic field, set up by coil 11, rises or falls relatively slowly since it varies in accordance with the changes in the voltage in the armature. The latter in turn follows the changes of current in the field. Accordingly 45 in voltage regulators embodying only a coil such as is indicated at 11, the opening and closing movements of contacts 6 and 7 are of relatively low frequency, i. e., of the order of 10 to 40 cycles per second.

Means are provided for speeding up the action of the contacts whereby the movement thereof is increased to a relatively high frequency, as for example, 80 to 300 or more cycles per second. For this purpose the core 50 10 carries a second or auxiliary winding 13

which is connected in series with a pair of resistances 14 and 15, and with the contacts 6 and 7 being connected across the generator field 2. Coil 13 is wound in such a manner as to strengthen the magnetic field set up in core 10 by the coil 11, and the number of ampere turns of both coils are so selected that the tension of spring 9 is overcome only when both coils coact to produce the desired strength of the magnetic field of the core 10.

When the contacts are closed, current flows from the positive output lead 4 through said contact resistances 15 and 14 and coil 13, the latter coacting with the coil 11 to set up the magnetic field in core 10. When the output 80 voltage of the generator exceeds a predetermined value, as determined by the setting of spring 9, the field of the electromagnet is sufficiently strong due to the combined action of coils 11 and 13 to overcome the tension of 85 spring 9 and move contacts 7 out of engagement with contact 6. The instant the contacts are opened, the current in coil 13 falls, thus producing a sudden decrease in the flux 90 of core 10 and this decrease is independent 95 of the fall of the voltage in the armature 1. The regulator armature 8 instantly moves to re-engage contact 7 with contact 6 due to the action of spring 9. A much quicker action 100 of the contacts is thus obtained than results from the use of a single coil such as coil 11, since the magnetic field produced by the latter falls relatively slowly in accordance with the drop of voltage in the armature of the generator.

The use of the second or auxiliary coil 13 in combination with the coil 11 is sufficient to raise the frequency of the contacts to as high as 80 to 300 cycles or more per second. This change in the frequency of the contacts may 105 not entirely eliminate the intermediate note resulting from the engagement and disengagement of the contacts, but the note will be of a much higher pitch than that of other sounds resulting from radio waves which may 110 be transmitted from a signalling system energized by the generator, and hence will not interfere with the reception of the signals at the receiving end.

During the operation of the voltage regulator, a certain amount of sparking would normally occur at the contacts which would tend to fuse the latter together and thereby 115 destroy the action of the regulator and possibly produce hazardous failures in the generator supply system. This is particularly true when the voltage regulator is employed with a generator in which the generator field has a relatively high inductance, because such high inductance causes a sudden voltage 120 surge to be induced therein by self-induction due to collapsing and building up of the magnetic field in the generator field winding. The excessive sparking also tends to produce 125 electrical oscillations which have a disturbing 130

effect upon electrical circuits connected to or operated in the vicinity of the generating equipment, particularly radio receiving systems which are highly sensitive to very slight disturbances. It is therefore desirable to suppress these disturbing oscillations and prevent the fusing of the regulator contacts, and to this end novel means are provided whereby the excessive sparking across the contacts is substantially eliminated and prevented.

In the form shown, the means last referred to comprise an impedance network embodying a pair of parallel circuits including impedance elements which are constituted by the regulator winding 13, generator field winding 2, resistances 14 and 15, and a condenser 16 of suitable capacity. Condenser 16 has one side thereof connected to the junction point between the resistances 14 and 15 and the other side to a lead which connects the coil 13 to the negative output lead 5, and forms the two parallel circuits mentioned above. One of said parallel circuits includes the field winding 2, the resistance 15, and the condenser 16 in series therewith, and the other parallel circuit also includes condenser 16 and resistance 14 and the regulator winding 13 in series therewith. It will be apparent from this circuit arrangement that when the contacts 6 and 7 are open, condenser 16 and the resistance 15 are in series with the generator field 2 so that the self-induced electromotive-force produced in the field winding 2 by the opening of the contacts, will cause the condenser 16 to become charged, and the charge which has thus accumulated in the condenser will then be discharged through the resistance 14 and the winding 13, due to the relative impedance of the field being higher than that of the regulator winding, and will be dissipated therein, at or after which time the contacts close. It is essential, however, that the values of the resistances 14 and 15, the winding 13 and the condenser 16 be so selected and arranged that the charging of the condenser continues until the self-induced electromotive-force collapses at which time the condenser will discharge through the resistance 14 and the winding 13, thereby dissipating the charge and preventing sparking across the contacts 6 and 7.

There is thus provided a novel circuit arrangement whereby sparking across the voltage regulator contacts is substantially eliminated and the radiation of disturbing oscillations, due to such sparking, prevented. The elimination of the sparking also prevents the contacts from being fused together and prolongs the life of the contact points. The arrangement is extremely simple and much more efficient than devices of the prior art in that the sparking and the disturbing oscillations are suppressed without passing through the regulator contacts.

While only one embodiment of the invention has been illustrated and described, changes and modifications which will now appear to those skilled in the art, may be made without departing from the scope of the invention. For example, the auxiliary coil 13 may be eliminated, and the resistance 14 connected to the coil 11 instead, thereby providing a voltage regulator of the conventional type without destroying the effect of the novel spark preventing means of the invention. Reference is therefore to be had to the appended claims for a definition of the limits of said invention.

What is claimed is:

1. The combination with a direct current generator having a field winding of relatively high inductance, of a voltage regulator having relatively movable contacts and a pair of magnet coils for operating the latter, a resistance in series with the field winding and adapted to be shunted by the contacts when the latter are closed, and means associated with said field winding and one of said magnet coils for suppressing the electromotive-force induced in the generator field by the operation of the contacts, to prevent sparking across the latter.

2. The combination with an electric generator including a field winding, of a voltage regulator having relatively movable contacts and a pair of magnet coils adapted to be energized from said generator for operating said contacts, and means associated with the field winding and one of the coils and arranged for storing an electrical charge produced by an electromotive-force induced in the field winding when the contacts are open and to dissipate said charge when the induced electromotive-force collapses and before the contacts are closed, to prevent sparking across the latter.

3. In an electrical circuit, the combination of a winding having a relatively high inductance, an electrical circuit making and breaking device having contacts and an actuating winding therefor, a resistance element normally in series with said inductance winding and adapted to be short-circuited by said device, and means associated with said inductance winding and said actuating winding for dissipating the electrical energy produced in the inductance winding by the operation of the contacts, to prevent sparking across the latter.

4. In an electrical circuit, the combination of a winding having a relatively high inductance, an electrical circuit making and breaking device for controlling the current flow through said winding, a resistance element normally in series with said winding but adapted to be short-circuited by said device, a pair of magnet windings arranged to operate the contacts of said circuit making and breaking device upon the occurrence of predeter-

mined conditions in the electrical circuit, and impedance means associated with the inductance winding and one of the magnet windings and arranged for storing an electrical charge produced by an electromotive-force induced in the inductance winding when the contacts are open and to dissipate said charge through said magnet winding when the induced electromotive-force collapses and before the contacts are closed.

5. In combination, a generator including a field winding, a voltage regulator having relatively movable contacts and an electro-magnet for operating the latter upon a voltage change in the generator, and means for preventing sparking across said contacts due to an electromotive-force induced in the generator field winding by the operation of said contacts, said last mentioned means comprising a pair of parallel circuits, one of which includes a condenser, a resistance and the generator field winding, and the other of which also includes said condenser and a resistance and the winding of the electro-magnet and the relative impedances of said parallel circuits being such that the condenser is charged by the counter electromotive-force induced in the field winding when the contacts are open, and discharged through the winding of the electro-magnet when the induced electromotive-force collapses and before the contacts are closed.

6. In combination with a generator having a field winding and a field resistance means for regulating the output voltage of said generator by intermittently placing said resistance in circuit with said field winding including a pair of contacts, means including an electro-magnet for controlling the engagement of said contacts, said electro-magnet embodying a magnet coil in series with said contacts and in parallel with said winding, and another magnet coil in parallel with said contacts, and means associated with one of said magnet coils and said field winding for preventing sparking across said contacts due to an electromotive-force induced in said field winding by the operation of said contacts.

50 7. In combination with a generator having a field winding and a field resistance, means for regulating the voltage output of said generator by intermittently placing said resistance in circuit with said field winding including a pair of coacting contacts, means including an electro-magnet for controlling the engagement of said contacts, said electromagnet embodying a magnet coil in series with said contacts and in parallel with said winding, and another magnet coil in parallel with said contacts, and means associated with said field winding and said series magnet coil for preventing sparking across said contacts due to the electromotive-force induced in said field winding by the operation of said contacts.

8. In combination with a generator having a field winding of relatively high inductance and a field resistance, means for regulating the output voltage of said generator by intermittently placing said resistance in circuit with said field winding including a pair of coacting contacts, means including an electro-magnet for controlling the engagement of said contacts, said electro-magnet embodying a magnet coil in series with said contacts and in parallel with said field winding, and another magnet coil in parallel with said contacts, and means for preventing sparking across said contacts due to the electromotive-force induced in said field winding by the operation of said contacts, said last mentioned means comprising a pair of parallel circuits, one of which includes a condenser, a resistance and the generator field winding, and the other of which also includes said condenser, a resistance and the series magnet coil, the relative impedance of the two-parallel circuits being such that the first circuit is adapted to charge said condenser during the time that the contacts are open and the second circuit is adapted to discharge said condenser through the magnet coil when the induced electromotive-force is collapsed and before the contacts are closed.

9. The combination with an electrical circuit including a winding of relatively high inductance and a resistance normally in series with said winding of a movable-contact device for intermittently short-circuiting said resistance to control the flow of current through said inductance winding, an electro-magnet arranged to be energized from said electrical circuit for controlling the operation of said movable-contact device upon the occurrence of predetermined conditions in said circuit, and means for preventing sparking across the contacts of said movable-contact device due to the electromotive-force induced in said inductance winding by the operation of said contact device, said last mentioned means comprising a pair of parallel circuits, one of which includes a condenser, a resistance and the inductance winding in series, and the other of which also includes said condenser, a resistance and the winding of the electro-magnet in series, the relative impedance of said parallel circuits being such that the first will be effective when the contacts of the contact device are open to cause the induced electromotive-force produced in the inductance winding to charge the condenser, and the second circuit arranged to be effective upon collapsing of the induced electromotive-force and before the closing of the contacts to dissipate the charge from said condenser through the winding of the electro-magnet and the resistance associated therewith.

10. In combination, a winding having relatively high inductance, an electrical cir-

cuit making and breaking device for controlling the current flow through said winding whereby an electromotive-force is induced therein, said device having actuating windings for operating it, and means associated said inductance winding and one of the actuating windings of said circuit making and breaking device for dissipating the induced counter electromotive-force so that
10 sparking across the contacts of said circuit making and breaking device is prevented.

11. The combination with a direct current generator having a field winding, of a voltage regulator therefor having relatively
15 movable contacts and an actuating winding for operating the latter, the operation of which tends to produce disturbing electrical oscillations due to sparking at the contacts caused by an electromotive-force induced in
20 the field winding of the generator, and means associated with the field winding and the actuating winding adapted to accumulate the charge produced by the induced electromotive-force when the contacts are open, and to
25 dissipate said charge upon collapsing of the induced electromotive-force and before closing of the contacts to prevent such sparking across the latter, thereby eliminating the disturbing electrical oscillations.

30 12. The combination with a direct current generator of a voltage regulator therefor having relatively movable contacts, the operation of which tends to produce disturbing electrical oscillations due to sparking at the
35 contacts caused by an electromotive-force induced in the field winding of the generator, and means adapted to accumulate the charge produced by the induced electromotive-force when the contacts are open, and to dissipate
40 said charge upon collapsing of the induced electromotive-force and before closing of the contacts to prevent such sparking across the latter, thereby eliminating the disturbing electrical oscillations, said last mentioned
45 means comprising an impedance network including the field winding of the generator, the winding of the voltage regulator and a pair of resistances in series therewith, and a condenser which is connected in parallel with
50 the field winding and the regulator winding.

In testimony whereof I have signed this specification.

PAUL H. MAURER.
